UNITED STATES PATENT OFFICE.

WILLIAM A. THAYER, OF SYRACUSE, NEW YORK.

PACKAGE GRABBER.

Application filed November 10, 1924. Serial No. 748,900.

To all whom it may concern:

Be it known that I, WILLIAM A. THAYER, a citizen of the United States, residing at Syracuse, in the county of Onondaga and State of New York, have invented certain new and useful Improvements in Package Grabbers, of which the following is a specification.

This invention relates to improvements in grabbers, designed for use by storekeepers, for removing packaged goods from shelves and the like, and has for its object to provide a novel and simple device of the class, by which packages of different size and of relatively heavy weight may be readily and safely gripped and lowered, from shelves that are beyond the reach of the store attendants. A further object is to provide a device of the class, whose gripping jaws are arranged to be manually opened for receiving the packages, and which thereafter holds the packages firmly gripped, by the gravitation of certain of the working parts. A further object is to provide a gripping mechanism, which automatically adjusts itself to packages of different size and shape. And a further object is to generally improve and simplify the construction, arrangement and operation of package handlers of the class.

I attain these objects by the means set forth in the detailed description which follows, and as illustrated by the accompanying drawing, in which—

Figure 1 is a top end view of the complete device; showing the gripping arms closed. Fig. 2 is a similar view; showing the arms extended and gripping a square package. Fig. 3 is a right side elevation, viewed in the direction of the arrow in Fig. 1. Fig. 4 is a front side elevation, viewed in the direction of the arrow in Fig. 3. Fig. 5 is a broken front side elevation; showing the gripping jaws extended and embracing a rectangular package. Fig. 6 is an enlarged top end view; showing a cylindrical, package held by the jaws. Fig. 7 is a top-plan view of one of the gripping members. And Fig. 8 is a view of the triangular head of the operating rod.

In the drawing, 2 represents a relatively long round handle, preferably made of wood, whose top end is reinforced and protected by a metal ferrule 2'. The top end of the pole 2 is bored out eccentrically to receive a round metal post or rod 3, which is preferably held rigid by the ferrule. This

rod projects several inches beyond the handle, and its top end is threaded and fitted with nuts 3'—3", between which the grabbing or gripping members or jaws 4—4' are pivotally secured, for operation like the blades of a pair of shears, in a plane at right angles to the axis of the handle. The members 4—4' are substantially Z-shaped and are alike in all respects, except that the member 4' is reversed when the parts are assembled, as shown in Figs. 1, 2 and 6. Each member comprises an operating arm 4^a, and a gripping arm or jaw 4^b, the latter being bent at right angles intermediate its ends, to form a shallow hook, in whose bight 4^c, the corner of a square package, as A, or one side of a cylindrical article, as B, may be disposed. The arms 4^a of the jaws are perforated at 4^d, to receive the support 3, and the free ends of said arms are correspondingly perforated, for attaching a common operating medium. When the members 4—4' are reversed, as shown in Figs. 1, 2 and 6, the bights 4^c of the several angular portions 4^b face each other, and the jaws 4^b may be readily adjusted for gripping relatively small, as well as relatively large articles, as shown in Figs. 1 and 2. The gripping jaws 4^b are preferably partially covered with rubber, or other cushion and adhesive material, as 4^e, for preventing injury to, as well as, the accidental release of the articles, while the latter are being removed from a shelf. The arms 4^a of the members are preferably mounted one upon the other, with their broad dimensions disposed horizontally, while the jaws 4^b have their broad dimensions arranged vertically. This is accomplished by giving the jaws a quarter-twist, as indicated at the bends 4^f. The jaws of the members 4—4' are opened and closed scissors-fashion, by an operating rod 5, which is reciprocatable on the front side of the handle 2, by means of loop screws 5', which are disposed at intervals along the handle. The lower end 5^a of the rod 5 is bent outwardly for facilitating the manipulation of the rod. The top end of rod 5 is bent outwardly away from the handle, as at 5^b, and is then bent inwardly at right angles, as at 5^c, and the free end of the latter portion being flattened, and perforated to receive and slide on the support 3. The rod 5 is operatively connected with the arm 4^a of the gripping members, by means of an open triangular loop 6, whose arms 6'—6^a are inserted downwardly through the per-

forated ends of the portions 4^a, as best seen in Figs. 1, 2 and 6. The lower ends of the loop-arms 6'—6^a straddle the bent portion of the rod 5, to which they are pivoted by a pin 6^c. The normal disposition and arrangement of the operating parts, are as shown in Figs. 1, 3 and 4, wherein the jaws 4^b are held in the closed and partially overlapped position, by the gravitation of the operating rod 5 and the triangle 6. The jaws 4^b are opened for effecting the grabbing of packages, as A and B, by the operator forcing the rod 5 and triangle 6 upwardly, as shown in Figs. 2 and 5. This upward movement of the rod 5 and the loop 6 swings the arms 4^a from the position shown in Figs. 1, 3 and 4, to that shown in Figs. 2 and 5 in which the free ends of the arms 4^a have been moved toward each other, for spreading the gripping arms 4^b sufficiently to permit the claw-like extremities 4^x of the jaws to be inserted between or around an article, as A or B; after which the operator lets go the rod 5 and the latter instantly gravitates until all of the looseness or slack of the parts is taken up and the claws 4^x firmly grip the package, as shown in Figs. 2 and 6. The operator may then remove the package from the shelf, and lower it without danger of the package being accidentally released. In practice my improved gripper readily and safely handles packages weighing from ten to fifteen pounds.

Obviously, by slightly changing the shape and arrangement of the gripping members 4—4', my device may be employed for a variety of uses, such as harvesting apples, peaches, and the like.

Having thus described my invention, what I claim, is—

1. In a device of the class described, an elongated handle, a post embedded in the top of the handle, an operating rod reciprocatable on the handle and having a bent portion which engages and slides on the said post, a pair of oppositely arranged gripping members pivotally mounted near the

top end of said post adapted to be moved toward and from each other shear-fashion, means for securing the said members in place, and a triangular member pivoted to the said operating rod and slidably engaging the corresponding perforated ends of said gripping members. 50 55

2. In a device for removing packages from shelves, the combination of an elongated handle, a post eccentrically mounted on the top end of said handle, an operating rod, said rod being movable relatively to the handle, one end of said rod being perforated for receiving and sliding on said post, a pair of angular gripping members pivoted to the free end of said post and having perforated arms, and a triangular loop supported by and movable with the operating rod, the corresponding portions of said loop passing through the perforated arms of said members and adapted to operate said members shear-fashion, by raising and lowering of 70 60 65 the operating rod.

3. In a package grabber, a handle, a post supported by and projecting beyond the handle, the top end of said post being threaded, a pair of grabbing jaws having perforated 75 arms for pivotally mounting the jaws upon said post, the free ends of said arms being perforated, nuts engaging the threads of said post for holding the said jaws in place, a triangular member for moving said jaws 80 towards and from each other for grabbing and releasing packages, the corresponding arms of said triangle passing through the perforated arms of the jaws and adapted when raised and lowered to open and close 85 the claw-ends of said jaws, and an operating rod reciprocatably mounted on said handle, the top end of said rod being bent towards the handle and being perforated for receiving and sliding on said post, a bent 90 portion of said rod being disposed between the arms of the triangle and pivotally secured thereto.

In testimony whereof I affix my signature.

WILLIAM A. THAYER.
